(57) **CLAIM**

The ornamental design for a hair cutting razor, as shown and described.

DESCRIPTION

1. Hair cutting razor

Figure 1.1 : is a perspective view of a hair cutting razor;
Figure 1.2 : is a front elevational view; the back view is a mirror image thereof;

Figure 1.3 : is a top plan view;

Figure 1.4 : is a bottom plan view;

Figure 1.5 : is a right side elevational view;

Figure 1.6 : is a left plan view; and

Figure 1.7 : is an enlarged cross sectional view taken along line 7-7 in Figure 1.2.

The broken lines in the figures show portions of the hair cutting razor that form no part of the claimed design.

1 Claim, 6 Drawing Sheets(56)
